INVENTOR

UNITED STATES PATENT OFFICE.

WARREN M. BRINKERHOFF, OF AUBURN, NEW YORK.

DESIGN FOR A SECTION-KNIFE FOR MOWING-MACHINES.

SPECIFICATION forming part of Design No. 26,778, dated March 16, 1897.

Application filed January 26, 1897. Serial No. 620,835. Term of patent 14 years.

To all whom it may concern:

Be it known that I, WARREN M. BRINKERHOFF, a citizen of the United States, residing at Auburn, in the county of Cayuga and State 5 of New York, have invented and produced a new and original Design for a Section-Knife for Mowing-Machines; and I do hereby declare the following to be a full, clear, and exact description of the same, referenced being 10 had to the accompanying drawings, forming a part thereof.

My new and original design is illustrated in the accompanying drawings, in which—

Figure 1 represents a plan view of a section- 15 knife embodying my design, and Fig. 2 is a section-knife on line 2 2 of Fig. 1.

According to my design the section is formed with a butt or edge *a*, having short edges ex- 20 tending perpendicularly from said edge *a* and

indented, as at *b' b'*. From the front ends of 20 these indented edges inclined edges *b b* extend to the front end *c* of the knife. The inclined edges *b b* are beveled, as shown at *b' b'*. The section is also provided with two apertures *d d*, which are located adjacent to the 25 butt or edge *a*.

What I claim, and desire to secure by Letters Patent, is—

The design for a section-knife for mowing- 30 machines, substantially as herein shown and described.

In testimony whereof I affix my signature in presence of two witnesses.

WARREN M. BRINKERHOFF.
